[57] CLAIM

The ornamental design for a disposable panty pad, as shown.

DESCRIPTION

FIG. 1 is a top perspective view of a disposable panty pad, showing my new design;

FIG. 2 is a cross-section taken on line 2—2 of FIG. 1; and

FIG. 3 is a bottom perspective view with the peel-away protective sheet partly removed from the panty pad.

FIG. 1

FIG. 3
